CYLINDER REBORING-PLATE

Edward R. Michener, St. Louis, Mo., assignor to
 H & H Machine & Motor Parts Company, St.
 Louis, Mo., a corporation of Missouri

Application October 9, 1935, Serial No. 44,139

2 Claims. (Cl. 77—62)

This invention relates to a certain new and useful improvement in cylinder reboring-plates.

In the reboring of the worn cylinders of the engine or motor of an automobile, it is, so far as I am aware, the present general practice, necessitated by the structure of the engine and automobile, to first remove the cylinder-block from the chassis and then remove the cylinder-block head and its securing-studs, as well as also the valves and pistons and their associate parts, to permit proper operative placement of the cylinder boring-tool,—a practice both time and labor consuming and consequently more or less expensive.

My invention has hence for its chief object the provision of means in the form generally of an apertured plate for attachment to and upon the cylinder-block for permitting placement of the tool for efficient, expeditious cylinder-reboring without dismantling of the motor or removal thereof from the chassis.

And with the above and other objects in view, my invention resides in the novel features of form, construction, arrangement, and combination of parts presently described and pointed out in the claims.

In the accompanying drawing,—

Figure 1 is a plan view of a cylinder surface reboring-plate embodying my invention, illustrated in applied boring or operative position on a cylinder-block or motor;

Figure 2 is a view of the plate and block taken approximately on the line 2—2, Figure 1;

Figure 3 is an inverted plan view of the plate; and

Figure 4 is a view of the plate and block taken approximately on the line 4—4, Figure 1, fragmentally also illustrating in outline a cylinder boring-tool in connection therewith.

Referring now more in detail and by reference characters to the accompanying drawing, which illustrates a preferred embodiment of my invention, A designates the cylinder-block of an internal combustion-engine, and B designates a cylinder-reboring tool of any standard type, the block A having a plurality of cylinders 1 and being, as is usual, equipped with a plurality of spaced, upstanding studs 2, 3, and 4, 4', for securing of the cylinder-head and also with a plurality of valves 5.

Heretofore, as I have stated, it is required, in reboring the engine-cylinders when worn, according to present day general practice, to not only remove the entire block A from the chassis

of the automobile, but to also remove the various head-securing studs and valves 5 for properly placing and securing the tool B upon the block A for efficient cylinder reboring.

According to my invention, however, I provide a rigid preferably metallic plate C of suitable thickness and preferably of oblong rectangular contour, as shown, conformable with the usual surface contour of the cylinder-block A, the plate C being formed on its under face with a plurality of depending legs 6 and lugs 7, 8, for supporting the plate C flatwise over, and in suitably spaced relation upwardly from the upper face of, the block A.

It will be understood that, prior to placement of the plate C on the block A, the usual cylinder-head, not shown, has been removed, leaving upstanding the head-securing studs 2, 3, 4, and 4', which vary in length, and it may be here stated that, when in operative position, the space intermediate the under face of plate C and the upper face of the block A is in width preferably slightly less than the length of the shortest studs 2. For then accommodating the upper end-portions of the shortest studs 2, the plate C is provided on its under face with openings in the form of recesses 9, and for likewise accommodating the upper end-portions of some of the remaining studs 3 and 4, the plate C is formed with openings in the form of transverse apertures; as at 10.

In addition, the depending lugs 7, 8, are each preferably formed with longitudinal bores, as at 11, opening at their lower end upon the under face of the plate and at their upper end in counter-bores, or recesses, as at 12, 12', in the upper face of the plate, for snugly accommodating some of the longer studs 4' and stud-engaging-members or nuts 13, 13', for detachably fastening the plate C tightly on and over the block A for boring operations. Preferably, as best seen in Fig. 4, the counter-bore or recess 13', which is in registration with the bore 11 of the lug 8, is of greater depth for accommodating a particular or specially constructed securing-member 13' for engaging a shorter stud 3.

For purposes presently appearing, the plate C is centrally provided with a pair of suitably spaced tapped openings 14, and, in addition, the plate C is formed with a suitable plurality of transverse openings, as at 15, for registration, the plate C being operatively disposed on the block A, with the respective cylinders 1 thereof.

Accordingly, in use and practice and for a cylinder reboring-operation, the head of the cyl-

inder-block A is removed, thereby exposing the usual studs, as well as also the pistons and their directly connected parts, the block A, however, remaining in installed position on the chassis and the valves 2 being undisturbed. The engine-pistons being now removed, the plate C is rested upon the block A with the respective studs 2, 3, 4, and 4', projecting upwardly with their upper ends disposed in the respectively registering openings or bores 9, 10, 11, the fastening members 13, 13', being then engaged with respective studs 3, 4', for rigidly securing the plate C in position flatwise over, and in suitably spaced relation from the upper face of, the block A, with its apertures 15 in boring-registration with the respective cylinders 1.

A tool B may now be disposed, and by means of securing screws 16 engaged with one or the other of the tapped-openings 14, secured firmly, upon the plate C for boring operations, the tapped-openings 14 permitting the tool B to be shifted on the block A for operating in the respective cylinders 1 thereof.

Thus the plate C enables a reboring operation to be quickly, efficiently, and expeditiously effected, the plate C eliminating the present necessity of dismantling the motor or removing the motor from the frame, with an accruing saving to a large degree in time, labor, and expense. The plate C may be readily manufactured, is exceedingly durable, and is most efficient in the performance of its intended functions.

It is to be understood that changes in the form, construction, arrangement, and combination of the several parts of the plate and in its engagement with the cylinder-block may be made and substituted for those herein shown and described without departing from the nature and principle of my invention.

Having thus described my invention, what I claim and desire to secure by Letters Patent is.—

1. An automotive engine cylinder reboring fixture for use with an engine block having stud

bolts upstanding from a plane-surfaced face thereof adapted to receive a cylinder head comprising, a metallic plate portion having an upper plane-surfaced face, legs on the lower side of the plate to engage the plane face of the cylinder block and having their ends terminating in a plane substantially parallel to the upper plane face of the plate, said legs being of sufficient length to position said plane face above the outer ends of the stud bolts and the plate being provided with openings to receive said stud bolts and being countersunk in its plane face around certain of said stud bolts, and means received upon the stud bolts within the countersunk recesses to thus rigidly secure the fixture in place and leave the outer face thereof unobstructed and in a plane substantially parallel with and spaced from the plane face of the cylinder block to receive and support a boring tool.

2. An automotive engine cylinder reboring fixture for use with an engine block having stud bolts upstanding from a plane-surfaced face thereof adapted to receive a cylinder head comprising, a metallic plate portion having an upper plane-surfaced face, legs on the lower side of the plate to engage the plane face of the cylinder block and having their ends terminating in a plane substantially parallel to the upper plane face of the plate, said legs being of sufficient length to position said plane face above the outer ends of the stud bolts and the plate being provided with openings to receive said stud bolts and being countersunk in its plane face around certain of said stud bolts, and means received upon the stud bolts within the countersunk recesses to thus rigidly secure the fixture in place and leave the outer face thereof unobstructed and in a plane substantially parallel with and spaced from the plane face of the cylinder block to receive and support a boring tool, said plate further being apertured for permitting free tool-access to the cylinders being bored.

EDWARD R. MICHENER.
